US0D1005876S

(12) **United States Design Patent** (10) Patent No.: **US D1,005,876 S**
(45) Date of Patent: ** Nov. 28, 2023

(54) **FINGER RING**

(71) Applicant: **BEBPOP S.R.L.**, Milan (IT)

(72) Inventor: **Beatrice Maria Bongiasca**, Milan (IT)

(**) Term: **15 Years**

(21) Appl. No.: **35/514,486**

(22) Filed: **May 13, 2022**

(80) **Hague Agreement Data**

Int. Filing Date: **May 13, 2022**

Int. Reg. No.: **DM/221219**

Int. Reg. Date: **May 13, 2022**

Int. Reg. Pub. Date: **Jun. 17, 2022**

(30) **Foreign Application Priority Data**
